UNITED STATES PATENT OFFICE.

LELAND SCOTT, OF ST. JOSEPH, MISSOURI, ASSIGNOR OF ONE-HALF TO LOUIS HUGGINS,
OF ST. JOSEPH, MISSOURI.

EXPLOSIVE-ENGINE.

1,097,475.

Specification of Letters Patent.

Patented May 19, 1914.

Application filed October 22, 1912. Serial No. 727,194.

To all whom it may concern:

Be it known that I, LELAND SCOTT, a citizen of the United States, residing at St. Joseph, in the county of Buchanan and State of Missouri, have invented certain new and useful Improvements in Explosive-Engines, of which the following is a specification:

My invention relates to engines of the internal combustion type and has for one of its objects the provision of an improved construction of explosive engine comprising a head secured within the cylinder and providing a cup-shaped piston within which the explosions take place, the head within the cylinder having a water jacket to keep it cool during the operation of the engine.

Another feature of my improved engine consists in providing a means for throttling the explosive mixture so that the pressure of the mixture is not impaired, the throttling being done at the entrance to the cylinder instead of at the entrance to the compression chamber.

Another object of my invention is the provision of an improved valve and operating mechanism by which the full charge is maintained within the compression chamber at all times.

My invention will be described in detail hereinafter and illustrated in the accompanying drawings, in which,

Figure 1 is a view in elevation of an engine cylinder constructed in conformity with my invention; Fig. 2, a vertical sectional view of the engine cylinder and crank case; and Fig. 3, a vertical sectional view on the plane 90° removed from the plane of the section in Fig. 2.

In the drawings similar reference characters will be used to designate corresponding parts throughout the several views.

My improved explosive motor comprises a crank case 1 and an engine cylinder 2 mounted on the crank case and having its lower portion 3 extended into the crank case. The upper portion of the cylinder 2 is formed with double walls spaced apart to provide a water jacket 4 surrounding the cylinder, and the lower extension 3 is also provided with a water duct 5 to feed water to a head 6 mounted in the cylinder 2, said head having double walls as shown to provide a water jacket 7 and having downwardly extending legs 8 with laterally ex-

tending flanges 9 that are secured to the lower end of the extension 3 of the cylinder 2, said legs 8 and flanges 9 being double walled to provide a water duct 10 to supply the water jacket 7 in the head 6, the lower end of the extensions 3 and the flanges 9 being provided with aligned openings 11 through which the water passes between the water ducts 5 and the conduits 10. The inner wall of the cylinder 2 is extended upwardly as shown at 12 and forms an annular flange within the cylinder head 13 and is provided with a series of openings 14 to supply the interior of the piston to be hereinafter described with the explosive mixture from the chamber 15 within the cylinder head 13. Mounted within the cylinder 2 is the piston 16 that is of the inverted cup-shaped type and reciprocates between the upper portion of the cylinder 2 and the head 6, said piston being provided with the packing rings 17 bearing against the inner wall of the cylinder 2 and the head 6 being provided with packing rings 18 that bear against the inner wall of the piston 16.

19 indicates the crank shaft suitably journaled in the crank case 1 and 20 the piston rod connecting said crank 19 and a cross pin 21 secured to the lower end of the piston 16, the lower portion of the cylinder 2 being slotted as shown at 22 to permit reciprocation of the piston 16. The upper portion of the piston 16 is provided with a plurality of openings 23 that are adapted to align with the openings 14 in the flange 12 at the upper end of the cylinder 2 when the piston 16 is in its uppermost position to permit the explosive mixture within the chamber 15 to enter the piston 16 while 24 indicate other openings in the piston 16 that are adapted to register with exhaust ports 25 in the cylinder 2 when the openings 23 are positioned as shown in Fig. 2 to admit the explosive mixture to the piston as heretofore stated.

26 indicates a valve casing communicating with the chamber 15, and 27 a rotary valve mounted within said valve casing and adapted to supply an explosive mixture to the chamber 15 during the operation of the engine. The valve 27 is rotated from the crank shaft 19 by means of a shaft 26 suitably journaled on the engine casing and provided with beveled gears 40 connecting one terminal of the shaft 26 with the crank shaft 19 and other beveled gearing 28 con-

necting the other terminal of the shaft 26 with the valve. The valve 27 is so timed that during the operation of the engine the valve will be opened to admit the explosive mixture to the chamber 15 when the crank shaft 19 has turned about 5° from the position shown in Fig. 2 and the valve will remain open while the crank shaft is passing through a segment of 200° , or until it has turned about 25° on the up stroke of the piston 16.

In the operation of the engine, it will be understood that the piston being in the position shown in Fig. 2, the interior of the piston 16 will be supplied with an explosive mixture from the chamber 15 through the openings 14 and the alined openings 23 in the piston 16 and the entrance to the explosive mixture to the piston will serve to drive out through the openings 24 and the exhaust ports 25, all of the exploded gases within the piston. The piston will then proceed downwardly and compress the gases therewithin against the head 6 and when the piston reaches the lowermost portion of its stroke and is about to return the charge within the cylinder will be fired by the spark plug 29, one of the openings 23 being at this time in alinement with the spark plug. The explosion within the piston 16 will serve to drive the piston upwardly and when the piston returns to the position as shown in Fig. 2, the operation will be repeated as heretofore described. In order to control the amount of explosive mixture entering the piston 16, I provide a valve comprising a dome-shaped cap 30 slidably mounted on the flange 12 and having top wall 31 with a central bearing 32 in which is rotatably mounted the lower end of a valve rod 33, said valve rod being threaded as shown at 34 to engage a threaded nut 35 mounted in an opening 36 in the cylinder head 13 and having an operating arm 37 secured thereto for actuating said valve rod 33.

In operation, it will be apparent that when the dome-shaped cap 30 is in its raised position as shown in Figs. 2 and 3,

the openings 14 are entirely exposed to admit a full charge to the interior of the piston 16. When it is desired to limit the charge the dome-shaped cap 30 may be moved downwardly by rotation of the valve rod 33 to regulate the space through which the explosive gases are permitted to pass to enter the piston 16.

Having thus described the invention what I claim is:—

1. In an explosive engine, a cylinder, a head rigidly mounted within said cylinder, an inverted cup-shaped piston reciprocally mounted therein and provided with apertures near its upper end, an annular flange on said cylinder, said flange being provided with apertures adapted to register with the apertures in said piston and means for controlling the flow of gas through the said apertures.

2. In an explosive engine, a cylinder, a head rigidly mounted in said cylinder, an inverted cup-shaped piston reciprocating in the cylinder and provided with apertures therein, an annular flange on said cylinder and provided with apertures adapted to register with the apertures in said piston, a dome-shaped cap slidably mounted on said annular flange adapted to regulate the intake of gas to the piston.

3. In an explosive engine, a cylinder, a head rigidly mounted therein, a piston reciprocally mounted in said cylinder, an annular flange on the cylinder, means for allowing the intake of gas in said piston, a dome-shaped cap adapted to surround the annular flange and forming a head for said cylinder, a rod connected to the cap and means for actuating said rod whereby the cap will be caused to reciprocate on the flange to regulate the intake of gas.

In testimony whereof I affix my signature in presence of two witnesses.

LELAND SCOTT.
